CLAIM

I claim the ornamental design for a double-fastened pocket, as shown and described.

DESCRIPTION

FIG. 1 is a perspective view of a double-fastened pocket, illustrated in an open position, showing my new design;

FIG. 2 is a front elevational view thereof, illustrated in a closed position;

FIG. 3 is a front elevational view thereof, illustrated in the open position;

FIG. 4 is a left-side elevational view thereof, illustrated in the open position, the right-side elevational view being a mirror image thereof;

FIG. 5 is a top plan view thereof, illustrated in the open position;

FIG. 6 is a bottom plan view thereof, illustrated with a cover flap in a closed position;

FIG. 7 is a cross-sectional view thereof, illustrated with the cover flap in the closed position and an internal fastener in an open position, taken generally along lines 7—7 of FIG. 6; and,

FIG. 8 is a cross-sectional view thereof, illustrated in the closed position, taken generally along lines 7—7 of FIG. 6.

The broken lines showing a person and a pair of shorts in FIG. 1 are included for the purpose of illustrating the invention in use, and form no part of the claimed design.

The dashed lines shown on the pocket represent stitches.
